(57) **CLAIM**

The ornamental design for a lighted aircraft wingtip as shown and described.

DESCRIPTION

FIG. 1 is an upper-left front perspective view of the lighted aircraft wingtip in accordance with an embodiment of the invention;

FIG. 2 is a lower-left, front perspective view of the lighted aircraft wingtip of FIG. 1;

FIG. 3 is a top plan view of the lighted aircraft wingtip of FIG. 1;

FIG. 4 is a bottom plan view of the lighted aircraft wingtip of FIG. 1;

FIG. 5 is a left end elevation view of the lighted aircraft wingtip of FIG. 1;

FIG. 6 is a front elevation view of the lighted aircraft wingtip of FIG. 5; and,

FIG. 7 is a rear elevation view of the lighted aircraft wingtip of FIG. 5.

The broken lines in the drawings are for purposes of illustrating the environment in which the lighted aircraft wingtip are used and form no part of the claimed design.
